United States Patent Office

Des. 191,927
Patented Dec. 12, 1961

191,927

UPRIGHT COOLER

Frank R. Trulaske, Grafton, Ill., assignor to True Manufacturing Co., St. Louis, Mo., a firm or copartnership

Filed Nov. 14, 1960, Ser. No. 62,837

Term of patent 14 years

(Cl. D67—4)

FIG. 1.

FIG. 2.

FIG. 3.

FIG. 4.

FIG. 1 is a front elevational view of an upright cooler showing my new design.

FIG. 2 is a side elevational view, thereof, the opposite side being the same.

FIG. 3 is an enlarged fragmentary cross-section taken on the line 3—3 of FIG. 1.

FIG. 4 is a fragmentary sectional view on the line 4—4 of FIG. 1.

The top and the back of the upright cooler are substantially plain.

I claim:

The ornamental design for an upright cooler, substantially as shown and described.
